ATTORNEY

UNITED STATES PATENT OFFICE.

EDWARD SIEVART, OF MANITOWOC, WISCONSIN.

MARINE PROPELLER.

1,349,981.

Specification of Letters Patent. Patented Aug. 17, 1920.

Application filed March 3, 1919. Serial No. 280,472.

To all whom it may concern:

Be it known that I, EDWARD SIEVART, a citizen of the United States, and resident of Manitowoc, in the county of Manitowoc 5 and State of Wisconsin, have invented certain new and useful Improvements in Marine Propellers; and I do hereby declare that the following is a full, clear, and exact description thereof.

- 10 My invention relates to new and useful improvements in marine propellers, more particularly of that type including a hub portion having radial blades curved transversely to procure propelling impact with the water.
- 15 It is in general the object of my invention to increase the propelling efficiency of devices of this character and it is more particularly my object to procure such arrangement and relation of the propelling blades that a portion 20 of the water engaged by one blade in its driving rotation is imparted momentum in a direction transverse to the rotative axis of the device for propulsion into the body of water immediately rearwardly of the hub of 25 the propeller, thus increasing the back-stop action of the water rearwardly of the propeller and consequently increasing the efficiency of the propeller, thus utilizing the entire surfaces of the blades for procuring 30 the propelling action.

It is further my object to procure this increased propelling action in a manner involving a minimum addition of structure in the device, thus conduced to a desired 35 simplicity of structure, with consequent advantages.

With the above and other objects and advantages in view, which will be apparent as the description proceeds, my invention 40 resides in the novel features of construction, combination and arrangement of parts as hereinafter more particularly described and defined by the appended claims.

In the accompanying drawings:

45 Figure 1 is an elevational view of a propeller constructed in accordance with my invention, and looking toward the rearward side of the propeller with respect to its direction of propelling movement.

50 Fig. 2 is an edge view of the propeller.

Fig. 3 is a transverse sectional view through the hub portion of the propeller on a plane indicated by the line 3—3 of Fig. 1.

55 Referring now more particularly to the accompanying drawings, 5 designates the hub portion of my improved propeller which

is provided with the usual keyed passageway whereby it may be mounted upon a drive shaft, and said hub portion is provided preferably adjacent one end with an annular 60 blade wall 6 disposed in a plane at right angles to the axis of the hub. From the periphery of this wall 6 there projects a plurality of, in the present instance two, blades 7, the inner portions of the blades 65 merging with and forming continuations of the surface of the blade walls. Each blade is twisted to lie at opposite angles oblique with respect to the plane of the blade wall 6, said blades being curved transversely to procure a maximum impact action on the water, the curvature of the blades being increased at their rearward sides with respect to the direction of rotation of said blades. These rearward sides of the blades, designated at a, 70 and which extend toward the eye in the side view shown in Fig. 1, have inner surface portions b which are curved forwardly with respect to the direction of travel of the propeller to merge into the wall portion 6, the 75 forward sides of the blade, with respect to their direction of rotation, being cut away at their inner portions as shown at c whereby to avoid the occurrence of surfaces which would be similar to the surfaces b but inclined in opposite directions.

Thus, in the operation of my improved propeller, the outer portions of the blades serve to effect impact engagement with the water in the usual manner directing said 80 water rearwardly to procure the major propelling action. At the inner portions of the blades however, particularly by reason of the undercut or forwardly inclined portions b an impact action is procured which tends to discharge the water transversely of the axis of the propeller, immediately behind the blade wall 6 whereby such water will be forced into the body of water immediately rearwardly of the hub of the propeller. 85

100 What is claimed is:

1. A propeller comprising a hub portion, an annular wall portion extending from the hub portion and disposed in a plane at right angles to the axis of the hub portion 105 and a plurality of blades extending radially from said annular wall portion and having their major portions curved transversely whereby they are disposed obliquely with respect to the plane of the annular wall portion, said blades having obliquely undercut rear surfaces on their inner portions 110

merging with the blade wall portion whereby to direct water transversely of the hub portion.

2. A propeller comprising a hub portion,
5 an annular wall portion extending from the hub portion and disposed in a plane at right angles to the axis of the hub portion and a plurality of blades extending radially from said annular wall portion and having their
10 major portions curved transversely whereby they are disposed obliquely with respect to the plane of the annular wall portion, said

blades having obliquely undercut rear surfaces on their inner portions merging with the annular wall portion whereby to direct 15 water transversely of the hub portion, and the forward inner edge portions of the blades being cut away adjacent the annular wall portion.

In testimony that I claim the foregoing 20 I have hereunto set my hand at Manitowoc in the county of Manitowoc and State of Wisconsin.

EDWARD SIEVART.
